UNITED STATES PATENT OFFICE.

FRANK C. WILLIAMS, OF PHILADELPHIA, PENNSYLVANIA, ASSIGNOR TO THE SAFETY BLOCK SIGNAL COMPANY, A CORPORATION OF DELAWARE.

RAILWAY SIGNAL AND STOPPING MECHANISM.

1,176,119.

Specification of Letters Patent. Patented Mar. 21, 1916.

Application filed December 14, 1910. Serial No. 597,187.

To all whom it may concern:

Be it known that I, FRANK C. WILLIAMS, a citizen of the United States, and a resident of Philadelphia, county of Philadelphia, and 5 State of Pennsylvania, have invented certain new and useful Improvements in Railway Signal and Stopping Mechanism, whereof the following is a specification, reference being had to the accompanying drawings.

10 This invention particularly relates to railway signals which are normally maintained in a "safety" position by a closed electric circuit, and which are arranged to shift by gravity to the "danger" position by short-circuiting or breaking said circuit, and which are connected with means coöperative with means 15 on a car or train to stop the same.

The principal objects of this invention are, to provide means arranged to automatically 20 control the motive power, and to actuate the brake setting mechanism of a car or train in accordance with the position of signals suitably disposed at intervals adjacent to the track, and normally maintained 25 in a "safety" position by a normally closed electric circuit, and arranged to be shifted to the "danger" position by short-circuiting or breaking said circuit; to provide auxiliary signals which are operatively connected 30 with each of the first mentioned or main signals, and which are normally maintained in the "danger" position by gravity, and arranged to be shifted to "safety" position by a normally open local electric circuit, closed 35 by the movement of their respective coöperative main signals to the full "danger" position; to provide said car or train with a normally closed electric circuit, operative to maintain the motive power and brake setting 40 mechanism in a position to permit the free movement of said train, and arranged to be short-circuited by said signal when in "danger" position, to effect the actuation of mechanism operative to stop said car or 45 train; to provide said car or train with a projecting member arranged to be shifted to effect the actuation of mechanism to stop the same; to provide mechanism mechanically connected with each of said signals to be 50 shifted in accordance with the position thereof, into or out of the path of the projecting member carried by said car or train to effect the stopping of the same; and to provide simple and efficient mechanism operative 55 to effect the movement of said signals.

The form of this invention hereinafter described provides a railway, which is divided into blocks or sections, with a main signal station located near the end of each block, each station comprising a semaphore 60 normally maintained in "safety" position by a closed electric circuit; an auxiliary signal station, comprising a semaphore, which is connected to be shifted in opposition to the semaphore at the main signal station; connections controlled by said semaphore to control the movement of cars or trains, and mechanism to shift said semaphores and maintain them in "safety" position, comprising a train of gears operatively connecting 65 a motor with each semaphore, and provided with a ratchet and a loosely mounted gear movable with respect to said train of gears, and carrying a pawl in engagement with said ratchet, a normally open electric 70 circuit local to said station, and including said motor, a lever or switch arranged to be shifted to close said circuit, and having a detent operative to maintain the semaphore in "safety" position when shifted thereto 75 by the action of said motor.

This invention also includes all of the various novel features of construction and arrangement hereinafter more definitely specified.

In the accompanying drawings, Figure 1 is a fragmentary vertical sectional elevation of a locomotive and tender, together with a diagrammatic illustration of a block signal unit; Fig. 2 is a transverse vertical sectional elevational view showing the front of a locomotive, and the signal in position to stop the same; Fig. 3 is a diagrammatic view showing the wiring of the block signal system, extended in a plane; Fig. 4 is 90 an enlarged elevational view of the mechanism at one of the signal stations, having one side of its casing removed to show the mechanism contained therein; and Fig. 5 is a transverse vertical sectional view of said 95 station taken on the line 5—5 in Fig. 4.

In said figures, the locomotive 6 and tender 7 are arranged to traverse the track rails 8 and 9, which are divided into blocks or divisions, by having the adjacent ends of one of the rails of each block separated by insulation 11, as best shown in Fig. 3. Disposed along the track and local to the ends of the adjacent blocks are the main signal stations 14, as best shown in Fig. 1, and 110

each main signal station is connected with an auxiliary signal station 15, disposed within each block at a suitable distance from the entrance end.

5 The main signal stations 14 are each provided with a semaphore 16, mounted upon the shaft 17, which is provided with a brush wheel 18 and the stop lever 19 arranged to limit the rotary movement of the shaft 17 by 10 engagement with the pin 20, in the downward movement of said semaphore 16, to the "danger" position, shown in Fig. 4, and at the right hand side of Fig. 3.

The brush wheel 18 is provided with a 15 contact brush 22, which is arranged to engage the sectoral plates 23, 24 and 25, which are alined concentric with respect to the shaft 17, and said brush is operative to contact with the sectoral plates 26 and 27, which 20 extend concentrically parallel with the plates 23, 24 and 25, as best shown in Fig. 4, the functions of which will be hereinafter described in detail.

The brush wheel 18 is in toothed engagement with the pinion 28 on the shaft 29, which is journaled in the frame 30. Said shaft 29 is also provided with the gear 31, which is in toothed engagement with the pinion 32 on the shaft 33, which is also 30 journaled in the frame 30 and which carries the gear 34, the ratchet 35, and the gear 36, which latter is loosely mounted on said shaft 33, and carries a pawl 37 in operative engagement with said ratchet 35, to permit the 35 relative rotation of the train of gears in the direction indicated by the arrows in Fig. 4, and to prevent their relative rotation in opposition to said arrows.

The gear 34 is in toothed engagement with 40 the pinion 38, which is secured on the shaft 39, journaled in the frame 30, upon which shaft is secured the fly fan 40 arranged to retard the too rapid movement of the gearing mechanism, and to prevent the jarring 45 of the semaphore when dropping to the "danger" position by gravity.

The gear 31, above referred to, is in toothed engagement with the gear 41 on the shaft 42, which is journaled in the frame 30, 50 and which carries the gear 43 in toothed engagement with the gear 44 on the shaft 45 of the electric motor 46, whereby the train of gears above described may be actuated to raise the semaphore 16 to its "safety" 55 position, when said motor is energized, in a manner hereinafter described.

The semaphore 16 is provided with a rearwardly extending tail piece 48 carrying the weight 49, arranged to counterbalance said 60 semaphore, and said tail 48 is also provided with the colored glass pane 50, which is presented in front of the bull's eye 51 of the lamp 52 when said semaphore 16 is disposed in the "danger" position. Said lamp 65 52 is supported upon the bracket 53 secured

to the signal casing 55, which, as best shown in Fig. 5, is provided with a removable side wall 56.

The mechanism at the auxiliary station 15 is electrically connected with the mechanism at the main station 14, and comprises gearing similar to the gearing in said station 14, and therefore the specific description of said gearing at the station 15 is deemed unnecessary, and any reference to 75 the parts thereof will designate the same reference numerals of the corresponding parts in the main signal station above described. It is to be noted that the semaphore 65 at said auxiliary station 15 is normally 80 to be maintained in the "danger" position in opposition to the normal position of the semaphore 16 at its respective main signal station 14. The brush wheel at the auxiliary signal station 15 is provided with a brush 85 67, which is arranged to engage the insulated contact plates 68 and 69.

The semaphores 16 are arranged to be retained in "safety" position by the detent lever 72, which has the detent 73 arranged 90 to engage the teeth of the gear 36 and which, at the main signal stations, is normally maintained in engagement with said gear by the magnet 75, which is energized by its connections through the wires 76 and 77 95 with the respective track rails 8 and 9, which are continuously charged by the batteries 78 of the respective blocks.

The detent lever 72 is pivoted at 80 to the contact terminal 81, and is provided with a 100 weight 82, arranged to counterbalance the free end of said lever, which is provided with a contact finger 83 arranged to engage the point 84 on the terminal contact 85, which is connected by the wire 86 with the 105 shaft 17, which latter is grounded by its connection with the undivided track 9 through the wire 88.

The semaphores 16 at the main signal stations 14 are released only by the presence of 110 a car or train in the block protected thereby, which short-circuits the line, including the wires 76 and 77 and the magnet 75, and permits the detent lever 72 to shift to the position shown in Fig. 4, and at the right hand 115 side of Fig. 3.

The movement of the mechanism at the signal station 14 to the "danger" position, closes the circuit through the wheel 18, brush 22, contact plate 23, wire 90, including 120 the battery 91, magnet 92 and wire 93, which effects the movement of the detent lever 94 at the auxiliary signal station 15 to the position shown in Fig. 3, whereby the semaphore 65 is retained in the "safety" position in the 125 same manner that the semaphore 16 at the signal station 14 is maintained in said "safety" position, as above described.

The movement of the semaphore 16 at the main signal station 14 to the "safety" posi- 130

tion, is effected by reestablishing the circuit through the magnet 75, which occurs when the car or train in the block protected by said semaphore passes from said block, and 5 which effects the movement of the detent lever 72 to the position indicated at the left hand side of Fig. 3, to afford contact between the contact finger 83 and the point 84 of the contact plate 85, thus forming a circuit, including said contact plate 85, through the wire 86, wheel 18, brush 22, wire 95, including the battery 96, to actuate the motor 46, the wire 98, terminal contact 81, and detent lever or switch 72.

10 As will be readily seen, the rotation of the motor 46 will rotate the train of gearing in the direction of the arrows indicated thereon in Fig. 4, independently of the gear 36, which is maintained in locked position 20 by the detent 73, during the rotation of said gearing train 11.

15 The closing of the circuit, including the motor 46 and the battery 96, is dependent upon the contact of the brush 22 with the contact plate 26, and, therefore, when the semaphore 16 reaches the position where said brush encounters the dead plate 27, said circuit will be broken and the motor will therefore cease to rotate, to prevent further 30 movement of the semaphore, which will be maintained in the position to which it has been shifted by said motor, by the engagement of the pawl 37 with the ratchet wheel 35.

35 The semaphore 16 will be maintained in the "safety" position by the closed electric circuit, including the wires 76 and 77 and the magnet 75, so long as the section or block protected by said signal remains clear, 40 but the moment that a train or car enters said block, the battery 78, which is connected to the rails of said block, is short-circuited. The magnet 75 being thus deenergized, permits the lever 72 to drop to the position 45 shown in Fig. 4, which effects the release of the gear 36 and permits rotation of the gearing train, and, consequently, the movement by gravity of the semaphore 16 to the "danger" position shown in said figure.

50 It will be seen that the circuit, including the motor 46, although connected through the contact plate 26 and the brush 22, when said semaphore is in the "danger" position, is not closed until the circuits, including the 55 wires 76 and 77, are reestablished, which is effected by the movement of the car or train from the block protected by said semaphore into the adjacent block, whereupon the magnet 75 is energized to effect the movement of 60 the lever 72, to close the circuit, including said lever, contact plate 85, wire 86, wheel 18, brush 22, contact plate 26, wire 95, battery 96, motor 46, wire 98 and the contact terminal 81.

65 In order to effect the automatic stopping

of the train, contact plates 100, 101 and 102 are disposed in alignment between the rails 8 and 9, the plates 100 and 101 being disposed at one side of the insulation to effect the stopping of the train before reaching the 70 signal station, and the plate 102 being disposed at the other side of said insulation to effect the stopping of the train in event of the semaphore remaining in a "safety" position after being passed by said train. 75

As best shown in Fig. 2, the contact plate 100 is connected by the wire 103 with the contact plate 23 at the main signal station 14; the contact plate 101 is connected by the wire 104 with the insulated section of track 80 rail 8 of the adjacent block, and the contact plate 102 is connected by the wire 105 with the contact plate 25 at said signal station 14.

The contact plates 100 and 101 are so disposed as to be engaged by the contact roller 85 108 carried by the tender 7, before reaching the insulation 11, which separates the ends of the adjacent blocks, when a train is traveling toward the left in Fig. 3, as indicated by the arrow in said figure, and the contact 90 plate 102 is disposed in such relation to the insulation 11 as to be engaged by the contact roller 108 after the train has passed into the section of track protected by the signal just passed. The longitudinal position of said contact plates is dependent upon 95 the speed of the trains and the curves and grades of the road.

The stopping mechanism carried by the locomotive 6 is connected to actuate the 106 throttle valve lever 109 to shut off the motive power and to contemporaneously actuate the train pipe valve 111 in the train pipe 112, to apply the brakes. Said stopping mechanism comprises the cylinder 113, 108 whose piston is connected with the valve 111, and is arranged to be actuated by the air pressure from the air brake system. The cylinder 113 is connected by the pipe 114 with the air pressure reservoir 115, which is 110 included in the air brake system.

The air pressure is admitted to the cylinder by the slide valve 116, which is connected with the piston and shifted in accordance with the movement thereof to admit and exhaust the pressure to and from the said cylinder 113. The train pipe valve 111 is provided with the lever 117, connected to be oscillated by the reciprocation of said piston to alternately open and close said valve to 115 effect the gradual setting of the brakes.

The admission of pressure to the cylinder 113 may be manually regulated by the valve 118 in the pipe 114, and automatically controlled by the motor valve 119, which is provided with the operating arm 120, arranged to be shifted by a weighted ball carried thereby, and normally tending to rotate the valve 119 by gravity to the open position. 125

The arm 120 is normally retained in po- 130

sition to close the valve 119 by the magnet 122, which is included in a circuit comprising the wire 123, wheel 124, frame 125, wheel 126, wire 127 having the battery 128, contact 5 roller 108 and the wire 129, which is normally closed to energize said magnet, to maintain the air brake system in its normal condition, operative to be controlled by the operator.

10 The automatic actuation of the stopping mechanism is effected when the contact roller 108 engages one of the contact plates 100, 101 or 102, and completes the circuit of least resistance through the signal station mechanism, which short-circuits the battery 128 and deenergizes said magnet 122 to release the arm 120, which immediately drops by gravity to a position to open the valve 119 and admit air pressure from the reservoir 115 to the motor cylinder 113.

20 The valve 119 is arranged to be automatically closed by the rack bar 133, which is provided with a projection 134 extending into the path of the lever 120, and arranged 25 to engage said lever and shift it to its normally closed position. Said rack bar 133 is provided with rack teeth and is intermittently shifted toward the right, with respect to Fig. 1, by the pawl 132, pivoted on the lever 117 in engagement with the teeth of said bar, until the projection 134 has shifted the lever 120 to the position to close the valve 119, and to be held by the magnet 122.

25 The valve 111 may be shifted to the closed position by the manual actuation of the resetting slide bar 135, which is arranged to engage the pawl 132, to uplift the latter from engagement with the teeth of the rack bar 133, so that said rack bar 133 may be 40 shifted with respect to said pawl to its normal position, by engagement of the projection 140, on the slide bar, with the abutment 141 on the rack 133. In shifting the rack bar 133 to its normal position, the abutment 45 141 engages the end of the pawl 132 to effect the movement of the lever 117 to its normal position to close the valve 111, whereupon the brakes may be manually controlled by the operator through the valve 136 in the 50 pipe 142, which connects the reservoir with the train pipe 12.

55 The motor mechanism may be actuated independently of the valve 119 in the pipe 114, which is provided with a by-pass connection, including the pipe 144, which is provided with a valve 145 having a controlling lever 146, extending oppositely from the center of oscillation, and provided at one end with a weight 147 tending to open 60 the valve 145 and at the other end with a notch 148 arranged to receive one end of a centrally pivoted lever 149, which is pivoted to the bracket 150 and arranged to maintain the valve closed, and has its free end 65 normally projecting laterally from the en-

gine, and arranged to be actuated in a manner to be hereinafter described.

The motive power of the locomotive is arranged to be shut off by the air pressure from the pressure reservoir 115, and to 70 effect such shutting off of the motive power a cylinder 152 is provided, which is supported on the boiler of the locomotive and is provided with a piston 153, which is connected with a bell crank lever 154, having 75 a hand grip 155 for its manual actuation. Said bell crank lever is pivoted to the throttle lever 109 and is connected to shift the lever bolt 156 to release said bolt from the sector 157.

80 The cylinder 152 is connected with the pipe 114, so that when the valve 119 is shifted to effect the setting of the brakes, pressure will be admitted into the cylinder 152, which will effect the forward movement of the piston 153 to release the lever bolt 156 from said sector, to permit the lever 109 to automatically shift to a position to shut off the motive power.

85 As shown in Fig. 2, the semaphore 16 is connected by the link 160 with the bell crank lever 161, which is pivoted at 162 in the casing 163 and connected by the link 164 with the bell crank lever 165, pivoted at 166 in the casing 167, and provided with 95 the weight 168, tending to shift said semaphore to the "danger" position shown in said figure.

90 The link 164 is provided with a slot 170, which is engaged by a pin 171 on the lever 172, carried on the vertical shaft 173, which is journaled in the bearing 174 and provided with the arm 175, arranged to swing in a horizontal plane into the path of the lever 149 of the valve 145 in the by-pass 105 connection pipe 144. If the engine proceeds to pass the arm 175, the lever 146 is engaged thereby and shifted to open the valve 145, which connects the reservoir 115 with the cylinder 113, whereby the stopping 110 mechanism is operated to stop the train, as above described.

115 It will be obvious that the arm 175 is shifted in accordance with the position of the semaphore 16, and when said semaphore is shifted to the "danger" position, shown 118 in Fig. 2, the arm 175 connected therewith will be shifted into the path of the lever 149, as shown in said figure, to effect the opening of the valve 145, but when said semaphore is shifted to the "safety" position, the arm connected therewith will be similarly shifted to a plane parallel with the track. To prevent the accidental displacement of the arm when in operative 125 position, the lever 172 is provided with a hook 176, arranged to be engaged with a detent 177, which is pivoted at 178, and arranged to be uplifted by the projection 179 130 on the lever 165.

The semaphore 65 at the auxiliary station 15 is similarly connected with the arm 180, which is operative to be swung into the path of the lever 149 to effect the stopping 5 of the train, and, as before noted, the semaphore 65 is normally in the "danger" position, and consequently the arm 180 will be in the "danger" position until shifted to the "safety" position by the movement of 10 the semaphore 16 to the "danger" position, and if for any reason the semaphore 16 fails to be shifted to said position, to protect the train which has just passed said semaphore 16, the arm 180 will be effective 15 to stop said train.

The mechanism above described operates as follows: Assuming the semaphore 16 to occupy the "danger" position, as shown at the main signal station at the right hand 20 side of Figs. 1 and 3, and in Fig. 2 of the drawings, and the operator, disregarding the warning signal, endeavors to enter the next block or division protected by said signal, the contact roller 108 engages the 25 contact plate 100, which short-circuits the battery 128 through the wire 103, contact plate 23, brush 22, wheel 18, wire 88, rail 9 and wheel 126, which deenergizes the magnet 122 and permits the arm 120 to 30 drop to the position to open the valve 119. If, however, the semaphore 16, for any reason, fails to drop to the "danger" position when a train occupies the block protected thereby, and a second train is permitted 35 to pass the contact plate 100, the engagement of the contact roller 108 with the contact plate 101 will short-circuit the battery 128 through the wire 104, track 8, the axles of the car in said block and track 9, 40 which will effect the stopping of the car in the same manner as when the battery 128 was short-circuited through the signal mechanism. Likewise, in event of the semaphore failing to drop to the "danger" position 45 after a car has entered the block protected thereby, the contact roller 108 will engage the contact plate 102, and the battery 128 will be short-circuited through the wire 105, contact plate 25 in the signal station, brush 22, wire 88, track 9, and the 50 wheels of said car, to effect the actuation of the stopping mechanism, and prevent the car from proceeding through the block which has not been properly protected.

If from any cause, such as the breaking of a wire, the polarizing of the batteries, etc., the signal system is rendered inoperative, it will be noted that the semaphore 55 65 and the arm 180 connected therewith, being normally maintained in the "danger" position, will be effective, visually, to indicate to the operator that the signals are not in proper working order, and will also be effective to automatically stop the train by the engagement of said arm 180 with the

valve lever 149, to open the pipe 118 through the by-pass connection 144. Similarly, if the operator endeavors to pass the semaphore 16 in "danger" position, and for any reason the contact roller 108 fails to make 70 contact with the contact plate 100, the arm 175 will engage the valve lever 149 to effect the stopping of the train mechanically, in the same manner as when engaged by the arm 180 connected with the semaphore 65. 75

It is not desired to limit this invention to the precise details of construction and arrangement herein set forth, as it is obvious that various modifications may be made therein without departing from the essential 80 features of the invention as defined in the appended claims.

Having thus described my invention, I claim:

1. In signal mechanism for railways, the 85 combination with a track divided into blocks and arranged to be traversed by a car or train, of a main signal station comprising a train of gears, a semaphore connected with one of said gears, means connected with said 90 gears to shift said semaphore to the "safety" position, and means to retain said semaphore in said "safety" position, a normally closed electric circuit including the rails of said track, and arranged to control said last 95 mentioned means, and an auxiliary station comprising a train of gears, a semaphore connected with one of the gears and normally maintained in "danger" position by gravity, and means operative to actuate said 100 gears to shift said semaphore to "safety" position, and controlled by the semaphore at the main signal station, and arranged to be shifted in opposition thereto.

2. In signal mechanism for railways, the 105 combination with a track divided into blocks and arranged to be traversed by a car or train, of a main signal station comprising a train of gears, a semaphore connected to be shifted by said gears to the "safety" position, means arranged to normally retain said 110 semaphore in said "safety" position, an auxiliary signal station comprising a semaphore, gears connected with said semaphore, means operative to actuate said gears to shift said semaphore to "safety" position, and means to retain said semaphore in "safety" position, and means operatively connecting said stations arranged to effect the actuation of said semaphore at the auxiliary station in opposition to the semaphore 115 at the main signal station.

3. In signal mechanism for railways, the 120 combination with a track divided into blocks and arranged to be traversed by a car or 125 train, of a main signal station comprising a train of gears, means including a normally open electric circuit operative when closed to actuate said gears to shift said semaphore to the "safety" position, a normally closed 130

electric circuit including the rails of said track operative to close said normally open circuit when said semaphore is in "danger" position, and to shift it to the "safety" position to break said normally open circuit, and means arranged to retain said gears to maintain said semaphore in "safety" position, an auxiliary signal station comprising a train of gears, a semaphore operatively connected therewith, a normally open electric circuit including means operative to actuate said gears when closed, and a normally open electric circuit connecting said stations and arranged to be closed by the movement 15 of the semaphore at the main signal station to the "danger" position, to close the normally open electric circuit at the auxiliary signal station, to shift said semaphore at said auxiliary station to "safety" position, 20 and to retain it in said "safety" position while the semaphore at the main signal station remains in said "danger" position.

4. In signal mechanism for railways, the combination with a track divided into blocks 25 arranged to be traversed by a car or train, of a main signal station comprising gears, a semaphore connected with one of said gears, means including a normally open electric circuit arranged to actuate said gears 30 to shift said semaphore to the "safety" position, a normally closed electric circuit including the rails of said track, arranged to close said normally open electric circuit when said semaphore is in "danger" position, to shift said semaphore to the "safety" 35 position, and means connected with said semaphore to break said normally open electric circuit when shifted to said "safety" position, an auxiliary signal station comprising gears, a semaphore, means including a normally open electric circuit arranged to actuate said gears to shift said semaphore to the "safety" position, and a normally open electric circuit connecting said signal 40 stations, operative to be closed by the movement of said semaphore at the main signal station to close the normally open electric circuit at the auxiliary signal station to shift the semaphore at said auxiliary signal station to the "safety" position, the circuit 45 connecting said stations being broken by the movement of the semaphore at the main signal station when shifted to "safety" position to release the semaphore at the auxiliary signal station and permit it to drop to the "danger" position.

5. In signal mechanism for railways, the combination with a track divided into blocks and arranged to be traversed by a car or 60 train, of a main signal station comprising gears, a semaphore connected with one of said gears, contact plates local to said signal station, a brush carried with said semaphore, a normally open electric circuit local to said station, including means operative when

closed to actuate said gears to shift said semaphore to the "safety" position, and means arranged to be shifted to close said local circuit and to retain said semaphore in the "safety" position to which it is shifted by the closing of said circuit, a normally closed electric circuit, including the rails of said track, arranged to shift said means to close said local circuit, and arranged to be short-circuited by said car or train to release said semaphore and permit it to drop by gravity to the "danger" position, an auxiliary signal station comprising gears, a semaphore arranged to be shifted thereby, contact plates, a brush carried with said semaphore operative to engage said contact plates, a normally open electric circuit, including one of said contact plates and means arranged to actuate said gears to shift said semaphore to the "safety" position when closed, and arranged to be broken by the movement of said semaphore to said "safety" position, and means operative to close said local circuit, a normally open electric circuit, including one of the plates at the main signal station, arranged to be closed through the brush at the main signal station, to shift the means at the auxiliary signal station to close the local circuit at the latter station, and to shift the auxiliary 95 semaphore to the "safety" position when the semaphore at the main signal station drops to the "danger" position.

6. In signal mechanism for railways, the combination with a track divided into blocks 100 and arranged to be traversed by a car or train, of a main signal station comprising gears, a semaphore connected to be shifted by said gears to the "safety" position, a motor arranged to actuate said gears, a contact plate, a brush carried with said semaphore arranged to engage said contact plate, a normally open electric circuit, including said motor and contact plate, arranged to shift said semaphore to the "safety" 105 position when closed, and to be broken by the disengagement of said brush from said contact plate when in said "safety" position, means operative to make and break said local circuit, independently of said brush, a normally closed electric circuit, including the rails of said track, arranged to actuate said making and breaking means to close said local circuit, means engaged by said making and breaking means operative to retain said semaphore in "safety" position, and arranged to be released to permit said semaphore to drop to the "danger" position by short-circuiting said normally closed electric circuit, which is normally effected by a car entering the block protected by said semaphore, an auxiliary signal station comprising gears, an auxiliary semaphore connected therewith and arranged to be shifted to the "safety" position thereby, a contact 115 120 125 130

- plate, a brush carried by said auxiliary semaphore and operable to engage said last-named contact plate, a normally open electric circuit local to said auxiliary station, 5 and including said brush and last named contact plate, and arranged to be closed when said auxiliary semaphore is disposed in the "danger" position, means to make and break said local circuit, and to retain 10 said auxiliary semaphore in "safety" position, independently of the brush carried therewith, and a normally open electric circuit arranged to shift the making and breaking means to close said local circuit to 15 actuate the gears to shift said semaphore to the "safety" position at the auxiliary station, when the semaphore at the main signal station is shifted to the "danger" position, and to release said semaphore at the auxiliary 20 station, by breaking the circuit connecting said stations when the semaphore at the main signal station is shifted to the "safety" position.
7. In signal mechanism for railways, the combination with a main signal station comprising a semaphore, and an electric circuit arranged to control said semaphore, of an auxiliary signal station on the same side of the track as said main signal station comprising a semaphore controlled by said 25 first mentioned semaphore and arranged to be automatically shifted in opposition thereto as a result of the shifting of said first-mentioned semaphore.
- 30 8. In signal mechanism for railways, the combination with a main signal station comprising a main semaphore, and an electric circuit arranged to control said semaphore, of an auxiliary signal station comprising an auxiliary semaphore, on the same side of the track as said main semaphore, and an electric circuit controlled by said main semaphore and arranged to shift said auxiliary semaphore in opposition to said main semaphore as a result of the shifting of said main 35 semaphore.
9. In signal mechanism for railways, the combination with a main signal station comprising a main semaphore, and a normally closed electric circuit arranged to control said semaphore, of an auxiliary signal station on the same side of the track as said main signal station comprising an auxiliary semaphore, and a normally open electric circuit controlled by said main 40 semaphore and arranged to shift said auxiliary semaphore in opposition to said main semaphore.
- 45 10. In signal mechanism for railways, the combination with a track arranged to be traversed by a train, of a main signal station comprising a main semaphore, and an electric circuit connected to said track and arranged to control said semaphore, of an auxiliary signal station on the same side of 50 the track as said main signal station comprising an auxiliary semaphore and an electric circuit local to said auxiliary station, 55 and including said brush and last named contact plate, a normally open electric circuit local to said auxiliary station, 60 and including said brush and last named contact plate, and arranged to be closed when said auxiliary semaphore is disposed in the "danger" position, means to make and break said local circuit, and to retain 65 said auxiliary semaphore in "safety" position, independently of the brush carried therewith, and a normally open electric circuit arranged to shift the making and breaking means to close said local circuit to actuate the gears to shift said semaphore to the "safety" position at the auxiliary station, when the semaphore at the main signal station is shifted to the "danger" position, and to release said semaphore at the auxiliary station, by breaking the circuit connecting said stations when the semaphore at the main signal station is shifted to the "safety" position.
- 70 11. In signal mechanism for railways, the combination with a main signal station comprising a main semaphore, and an electric circuit arranged to actuate said semaphore, of an auxiliary signal station comprising an auxiliary semaphore on the same side of the track as said main semaphore controlled by said main semaphore and arranged to be automatically shifted in opposition thereto as a result of the shifting of said main semaphore.
- 75 12. In signal mechanism for railways, the combination with a main signal station comprising a semaphore, and means to shift said semaphore, of an auxiliary signal station on the same side of the track as said main signal station comprising an auxiliary 80 semaphore controlled by said main station and arranged to be automatically shifted in opposition to said main semaphore as a result of the shifting of said first-mentioned semaphore.
- 85 13. In signal mechanism for railways, the combination with a track divided into blocks and arranged to be traversed by a train, of a main signal station comprising a semaphore, means to shift said semaphore to the "safety" position, means to retain said semaphore in "safety" position, and a normally closed electric circuit connected to said track and arranged to control said last 90 mentioned means, of an auxiliary signal station on the same side of the track as said main signal station comprising a semaphore normally maintained in "danger" position, and means controlled by said main semaphore to shift said auxiliary semaphore in 95 opposition to said main semaphore.
- 100 14. In signal mechanism for railways, the combination with a main signal station comprising an element movable from a "safety" position to a "danger" position, of an auxiliary signal station on the same side of the track as said main signal station comprising an element movable from a "danger" position to a "safety" position, and means including an electric circuit controlled by said first-mentioned element and arranged to shift said second-named element in opposition to said first-named element as a result of the shifting of said first-named element.
- 105 15. In signal mechanism for railways, the combination with a main signal station comprising an element movable from a "safety" position to a "danger" position, and normally maintained in "safety" position, of 110
- 120
- 125
- 130

- an auxiliary signal station on the same side of the track as said main signal station comprising an element movable from a "danger" position to a "safety" position, and
- 5   normally maintained in a danger position, and means including an electric circuit controlled by said first-named element and arranged to shift said second-named element in opposition to said first-named element as
- 10   a result of the shifting of said first-named element.
16. In signal mechanism for railways, the combination with a main signal station comprising an element movable from a "safety" position to a "danger" position, of an auxiliary signal station on the same side of the track as said main signal station comprising an element movable from a "danger" position to a "safety" position, and means including an electric circuit controlled by said first-named element and arranged to shift said second-named element in opposition to said first-named element as a result of the shifting of said first-named element, and
- 20   means controlled by said second-named element for stopping a car, said last-mentioned means being moved from an inoperative posi-

tion to an operative position as the result of the movement of said second-named element from a "safety" position to a "danger" 30 position.

17. In signal and stopping mechanism for railways, the combination with a track arranged to be traversed by a train, of a main signal station comprising a main semaphore 35 arranged upon one side of said track and an electric circuit connected to said track and arranged to control said semaphore, of an auxiliary signal station comprising an auxiliary semaphore, arranged upon the 40 same side of said track as said main semaphore, and an electric circuit connecting said auxiliary semaphore through said main semaphore and arranged to be controlled by said main semaphore to shift said auxiliary 45 semaphore in opposition to said main semaphore.

In witness whereof, I have hereunto set my hand this fifth day of December, A. D. 1910.

FRANK C. WILLIAMS.
